US00D494712S1

(12) **United States Design Patent** (10) Patent No.: **US D494,712 S**
Getgey et al. (45) Date of Patent: **** Aug. 17, 2004**

(54) **REPLACEABLE FLOSSER HEAD**

(75) Inventors: **William F. Getgey**, 421 Torrance Ct., Cincinnati, OH (US) 45202-1838;
Lewis Ray Dyson, Milford, OH (US);
Carl R. Andry, Lawrenceburg, IN (US)

(73) Assignee: **William F. Getgey**, Cincinnati, OH (US)

(**) Term: **14 Years**

(21) Appl. No.: **29/194,398**

(22) Filed: **Nov. 24, 2003**

Related U.S. Application Data

(63) Continuation-in-part of application No. 10/682,443, filed on Oct. 9, 2003.

(51) **LOC (7) CI.** **28-03**

(52) **U.S. Cl.** **D28/66**; D28/68

(57) **CLAIM**

The ornamental design for a replaceable flosser head, as shown and described.

DESCRIPTION

FIG. 1 is a front perspective view of a replaceable flosser head showing my design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left elevational view thereof; and,

FIG. 7 is a right elevational view thereof.

The broken lines shown in FIG. 1 are for illustrative purposes only and do not form part of the claimed design.

1 Claim, 2 Drawing Sheets

FIG. 4

FIG. 5

FIG. 6

FIG. 7
